[57] CLAIM

The ornamental design for a temperature insulating foam panel, as shown and described.

DESCRIPTION

FIG. 1 is a top plan view of a temperature insulating foam panel showing our new design.

FIG. 2 is a front view thereof.

FIG. 3 is a rear view thereof.

FIG. 4 is a left-hand side view thereof.

The appearance of the design from the right-hand side is a mirror image of that shown in FIG. 4.

The appearance of the bottom of the design is a mirror image of that shown in FIG. 1.

FIG. 1

FIG. 2

FIG. 3

FIG. 4
